The ornamental design for a connected spacer, as shown and described.

DESCRIPTION

FIG. 1 is a perspective view of a connected spacer of a new design, wherein the break lines indicate variable length; FIG. 2 is a top plan view thereof, wherein the break lines indicate variable length, the bottom being a mirror image; FIG. 3 is a right side view thereof, the left side being a mirror image; and,

FIG. 4 is a front view thereof, wherein the break lines indicate variable length, the rear being a mirror image. The broken line portion of the figure drawings is included to show unclaimed subject matter only and forms no part of the claimed design.

The break lines and a bracket are used to indicate that, for ease of illustration, the precise length of the connected spacer is not claimed. The appearance of any portion of the article between the break lines forms no part of the claimed design.
